UNITED STATES PATENT OFFICE.

FREDERICK H. EILERS, OF SAN FRANCISCO, CALIFORNIA.

TERRET.

SPECIFICATION forming part of Letters Patent No. 690,021, dated December 31, 1901.

Application filed August 19, 1901. Serial No. 72,521. (No model.)

To all whom it may concern:

Be it known that I, FREDERICK H. EILERS, a citizen of the United States, residing in the city and county of San Francisco, State of California, have invented an Improvement in Terrets; and I hereby declare the following to be a full, clear, and exact description of the same.

My invention relates to improvements in saddlery, and particularly to the terret or ring which is attached to the pad or saddle and hames of harness, through which the driving-reins pass.

Its object is to provide a means of readily inserting the reins into the terret and of detaching them therefrom without the necessity of passing the ends of the reins therethrough.

It consists of the parts and the constructions and combinations of parts which I will hereinafter describe and claim.

The figure is a view of my terret, parts of it shown in section.

A represents a terret having an opening or radial slot 2 in its periphery, adapted to pass a line readily through it. The base of the terret is suitably adapted, as by means of a screw-thread, to be secured in a socket in the pad or saddle. The opening 2 may be said to divide the terret into two members, which 30 may be designated by a. The adjacent ends of these members are each provided with a socket or casing 3, in which a ball 4 is retained. Seating in a bore in the base of each of these sockets and extending a short distance into the members a is a small helical spring 5, which bears also against the ball and presses the latter outward and against its neighbor, so offering peripheral projections beyond the sockets to close the opening 2. The diameter of the balls is a little greater than the width of this opening, after the parts are assembled, so that the balls are prevented from falling out. The socket-chambers are made cone-shaped, so as to allow 45 the balls to be pushed entirely within said chambers and give sufficient room for a rein to pass. These sockets are given a pitch outward, as shown, so that while the curve of the inner periphery of the terret members a is 50 continuous the point of contact of the balls is above the line representing the curved axis of the members a. The balls are thus nor-

mally supported against the upper walls of the sockets. Accordingly a less pressure downwardly or inwardly is necessary to separate the balls, as when the reins are inserted into the terret, than is required outwardly to spread the balls, as when it is desired to remove the reins. The lower edges 6 of the sockets are divergently inclined or 60 beveled, so that the plane of each beveled face is approximately tangential to its corresponding ball. Thus a rein cannot be unintentionally released from the terret, for a rein in sliding around either of the members a will always 65 strike the opposite member below the line of contact of the balls, and so will easily pass over the opening. A rein can only be removed from the terret when presented with its edge directly between the balls. The 70 amount of pressure in either direction, however, necessary to be used to part the balls must be very slight, so as not to mar or mark the leather. Accordingly the springs 5 are very light indeed. The pitch of the cone-shaped sockets and the bevel of the edges 6 are chiefly relied upon for the retention of the reins within the terret. The reins may be in the hands of the driver upon the box, and it is but the work of an instant to engage 80 or disengage the reins from the terrets.

Having thus described my invention, what I claim as new, and desire to secure by Letters Patent, is—

1. A terret having a portion of its periphery cut away and provided with sockets said sockets being given a pitch outward, and balls in said sockets, and means by which said balls may be made to contact with each other to close said opening. 85

2. A terret divided at one side to form a radial opening and the ends of the divided portion enlarged and formed with sockets which are given a pitch outward said sockets having their lower edges beveled, balls in said 95 sockets, and springs by which said balls are made to offer projections beyond said sockets and close the opening.

3. A terret having a radial opening in its periphery and the opposing ends of the terret enlarged and provided with sockets said sockets being given a pitch outward, spherical projections retained within said sockets, and springs by which said projections are made 100

to contact with each other to close said opening, said sockets having their edges beveled inwardly and divergently whereby the plane of each beveled face is tangential to its corresponding ball and the reins are held against accidental release.

4. A terret having a radial slot in its periphery, sockets in the walls of the slot and balls in said sockets and adapted normally to project into said slot, and having a diameter slightly greater than said slot, and springs acting against the balls, said sockets having

their lower edges inclined or beveled whereby the plane of each beveled face is approximately tangential to its corresponding ball, ¹⁵ substantially as and for the purpose described.

In witness whereof I have hereunto set my hand.

FREDERICK H. EILERS.
